H. BONER

SAW FOR SAWING TREES

Filed Mar. 16, 1921

UNITED STATES PATENT OFFICE.

HANS BONER, OF MADULEIN, SWITZERLAND.

SAW FOR SAWING TREES.

Application filed March 16, 1921. Serial No. 452,777.

To all whom it may concern:

Be it known that I, HANS BONER, mechanician, citizen of the Republic of Switzerland, residing at Madulein, in the Canton of the Grisons, Switzerland, have invented certain new and useful Improvements in Saws for Sawing Trees (for which I have filed an application in Switzerland March 8, 1920, Patent No. 87,001), of which the following is a specification.

The subject of the present invention is a saw for sawing down trees, an embodiment of which is represented on the accompanying drawing, viz:

Fig. 1 shows an elevation partly in section. Fig. 2 section along the line A—B of Fig.

1, and

Fig. 3 shows a side view.

Fig. 4 is a substantially longitudinal sectional view of the speed pulley gears and means for changing the operating speed of the machine.

a is a casing provided at two opposite sides with a slot *b* for the guidance of a push-rod *c* which carries the blade of the saw *d*. At each of these sides three plugs *e* are placed, capable of being turned and shifted, to which movable props *f* can be fixed. These props serve the purpose of supporting the casing on the ground.

The push-rod *c* is supported in the slots *b* by means of the nuts *g* through which pass spindles *h*. These are operated from a common shaft *k* by means of a pair of bevel gear-wheels *i*, so that the push-rod *c* can be shifted along the slots *b* parallel to each other. On the other hand the push-rod *c* can be shifted longitudinally thereof in the nuts *g*.

At the end of the shaft *k* exteriorly of the casing *a* a hand-wheel *l* is fixed and a chain-wheel *m* is loosely carried on said shaft. On the sides turned towards themselves the naves of *l* and *m* are fitted with clutch teeth in order to be able to connect *l* and *m* with each other. The coupling and uncoupling is done by means of an adjustable hand-lever *n*, which can be fixed firmly.

The chain-wheel *m* is driven by means of a chain *o* from the shaft *p* which is driven from a motor *q* by means of a chain *r* and a speed pulley-gearing *s*. Operating axially within the shaft *p* is a slide member 1 having a radially projecting lug 2 at its inner end and a knob 3 attached to the opposite end thereof outside of the shaft *p*. The wall of the shaft *p* is provided with a slot 4

extending substantially the entire length of the three gears *s'* which are loosely mounted upon the shaft itself and which are provided with keyways 5 cut longitudinally of their hubs. The lug 2 of the slide member 1 projects through the slot 4 and into one of the keyways 5 of the gears *s'* so that but one of the latter may be positively driven at a time. With this construction the change of speed of the gears is effected by moving the slide member 1 to any of the three positions possible to engage the gears on the shaft *p* with the driving gears *s*, in which case the two unengaged gears will rotate freely about the shaft *p* at rates of speed determined by the size of the driving gears. In operation it is only possible to change the speed of the device by first stopping the machine. On the shaft *p* a wheel *t* is fixed bearing near its circumference a lateral pin *u*, which engages a slot *v¹* of a frame *w*. A transverse plug *x* fixed to the push-rod *c* engages loosely a front slot *v²* parallel to *v¹* of frame *w* which consists of two plates, spaced apart 80 from each other. The frame *w* is so attached to two rods *y* parallel to the push-rod, that it can be shifted.

The turning of the wheel *t* therefore causes a shifting of the frame along the rods, forwards and backwards and this shifting imparts similar motion to the push-rod *c*, i. e. it moves the blade of the saw.

At the same time the screw-spindles *h* turn and therefore the blade of the saw 90 moves parallel to these and is moved forwards.

The drawing represents the saw in the position, in which it can saw through the trunk of a tree which is lying on the ground. But if the tree has to be sawn down, I take out the props *f* below to the right in Fig. 3, on both sides of the casing stick them above to the left in the plug *e* loosen the plug *e* (below to the left) so far that the casing *a* can turn 100 round them, turn the same to the left by 90°, fix the posts firmly and then the work can begin, the blade of the saw now lying horizontally. The latter is from time to time brought towards the trunk by means of the hand-wheel *m*, before the coupling between *l* and *m* is made and the motor is turned on.

In order to operate the motor *q* in either horizontal or vertical position, the carburetor may be constructed so that inlet and outlet 110 pipes form the journals about which the body of the carburetor revolves, as the posi-

tion of the device is changed. This type of construction is used to supply fuel to many of the aeroplane engines where the inclination of the latter are subject to sudden change.

Having described the nature of my invention, what I claim as new and desire to secure by Letters Patent of the United States is:—

10 A drag saw machine comprising a saw and means for reciprocating the same and for feeding it to the work transverse to the re-

ciprocation, such means for reciprocation comprising a guide frame or cross head slotted in the direction of feed of said saw, a rotating part having a pin, and a saw carrying bar having a pin, each engaged in the slotted cross-head so that the rotation of said part reciprocates the cross-head and the second pin travels therein during the feeding of the saw. 15

In testimony whereof I have affixed my signature. 20

HANS BONER.
